UNITED STATES PATENT OFFICE.

LEONARD B. BUCHANAN, OF WOBURN, MASSACHUSETTS.

RAIL-BOND PROTECTOR.

No. 854,328.

Specification of Letters Patent.

Patented May 21, 1907.

Application filed March 18, 1907. Serial No. 362,806.

To all whom it may concern:

Be it known that I, LEONARD B. BUCHANAN, of Woburn, county of Middlesex, State of Massachusetts, have invented an

5 Improvement in Rail-Bond Protectors, of which the following description, in connection with the accompanying drawings, is a specification, like characters on the drawings representing like parts.

10 Many rail-bonds are applied to the rails at the ball and notwithstanding many advantages obtained by applying rail-bonds to this particular part of the rails, certain objections arise, as for instance, the rail-bonds, 15 being exposed to view and readily accessible and being composed of copper, are very tempting to thieves, and they ply their vocation regardless of the disproportion between the profit to them and the cost to the company and the inconvenience and annoyance caused by delays due to removal of the rail-bonds. The bonds are also liable to be detached from the rails accidentally by wheels passing over them and they are also liable to 25 be deranged and disconnected by the pressure of the paving stones against them, due to many causes.

This invention has for its object to provide a protecting plate or shield for rail-bonds 30 which are attached to the rail at the ball, which is simple to construct and easy to apply and which very effectually protects the rail-bond in such manner that the above noted objections are overcome.

35 Figure 1 shows in front elevation a rail-bond protector or shield embodying this invention. Fig. 2 is a plan view of the rail-bond protector or shield shown in Fig. 1, removed from the rail. Fig. 3 is a transverse 40 section of the rail-bond protector or shield shown in Fig. 1, taken on the dotted line 3-3.

a and b represent the adjacent ends of two rails and c a rail-bond of any suitable construction, which is attached to the rails at the ball.

45 My protecting plate or shield consists of a piece of sheet metal, or it may be a casting, and comprises a bond-covering or inclosing portion d, herein shown as shaped to correspond with the shape of the rail-bond, and usually made flat, and having inturned ears or extensions d', d'', at each end adapted to bear against the ball of the rail at points out- 50 side of or beyond the rail-bond. Said ears or extensions are disposed at an obtuse angle

to the rails and act to hold the covering portion d at a suitable distance from the rail to provide a space behind it for the rail-bond, and also to divert wheels passing over it. 60 The said protecting plate or shield also comprises an attaching portion d', beneath the covering-portion d, which is usually made flat, and of suitable length to extend from rail to rail. Said attaching portion d' is 65 adapted to overlie the usual fish-plate e, and to be secured in place by the bolts e' which are employed to secure the fish-plate to the rails, said bolts passing through holes d'', see dotted lines Fig. 1, which are provided at the 70 opposite ends of said attaching portion, one or more of which may be in the form of slots so as to accommodate the varying positions of the fish-plate bolts.

75 As the rail-bond projects beyond the plane of the fish-plate, the covering-portion d will project beyond the plane of the attaching-portion d'. In other words said portions d and d' are offset with respect to each other. To obviate the formation of a pocket or 80 chamber by offsetting said portions which would be liable to catch and retain water, an opening is provided at the junction of said portions, at the lower edge of the covering-portion, for the escape of the water. 85

The attaching-portion of my protecting plate or shield, when constructed in the manner herein shown and described, also serves as an auxiliary fish-plate, which I deem a very desirable feature. 90

Having thus described my invention, what I claim as new and desire to secure by Letters Patent is:—

1. A protecting plate or shield for rail-bonds consisting of a bond-covering portion 95 and an attaching-portion, the latter adapted to extend from rail to rail and to overlie the fish-plate, and to be secured thereto, substantially as described.

2. A protecting plate or shield for rail-bonds consisting of a bond-covering portion having inturned ends and an attaching-portion, the latter adapted to extend from rail to rail and to overlie the fish-plate and to be secured thereto, substantially as described. 105

3. A protecting plate or shield for rail-bonds consisting of a bond-covering portion and an attaching-portion, the latter adapted to extend from rail to rail and to overlie the fish-plate, and to be secured thereto, said portions being offset with respect to each other, substantially as described. 110

4. A protecting plate or shield for rail-bonds consisting of a bond-covering portion and an attaching-portion, the latter adapted to extend from rail to rail and to overlie the fish-plate, and to be secured thereto, said portions being offset with respect to each other, and having an opening at their junction, substantially as described.
5. A protecting plate or shield for rail-bonds consisting of a bond-covering portion, shaped to occupy a position outside of and close to the bond to be protected and having inturned ends adapted to bear against the rails, and an attaching-portion adapted to extend from rail to rail and to overlie the fish-plate and to be secured by the fish-plate bolts, said portions being offset with respect to each other and having an opening at the lower edge of the covering portion, substantially as described.
6. A protecting plate or shield for rail-bonds attached to the ball of the rail consisting of a bond-covering portion extending out-

side of the bond, having ends turned at an obtuse angle in toward the rail adapted to deflect wheels of vehicles and an attaching-portion adapted to be secured by the fish-plate bolts, substantially as described.

7. A protecting plate or shield for rail-bonds attached to the ball of the rail consisting of a bond-covering portion extending outside of the bond, having ends turned at an obtuse angle in toward the rail adapted to deflect wheels of vehicles, and an attaching-portion offset with respect to the bond-covering portion, said plate having an opening below the bond-covering portion, substantially as described.

In testimony whereof, I have signed my name to this specification, in the presence of two subscribing witnesses.

LEONARD B. BUCHANAN.
